COMBINED DISTRIBUTOR HEAD AND IGNITION COILS

Filed Sept. 17, 1924

By *Clarence A. O'Brien.*

Attorney

UNITED STATES PATENT OFFICE.

WILLIAM MERRILL OLSON, OF OAK CITY, UTAH.

COMBINED DISTRIBUTOR HEAD AND IGNITION COILS.

Application filed September 17, 1924. Serial No. 738,193.

To all whom it may concern:

Be it known that I, WILLIAM M. OLSON, a citizen of the United States, residing at Oak City, in the county of Millard and State 5 of Utah, have invented certain new and useful Improvements in a Combined Distributor Head and Ignition Coils, of which the following is a specification.

This invention relates to a combined distributor head and ignition coil mounting adapted for use in automobile ignition systems, for replacing the usual distributor head as now used, and the separate ignition coil operating in connection therewith.

10 In the present construction of ignition system for automobiles, it is customary to mount the ignition coil on the dash board or other convenient part of the car, and connect the same by the proper wire connections to the contacts on the distributor and to the battery and controlling switch for the ignition circuit, which makes it necessary to provide a high tension wire connection between the distributor head and 15 the ignition coil, which frequently results in a loss of current, due to the difficulty of properly insulating this high tension wire.

The present invention therefore, is designed to eliminate numerous disadvantages 20 of the present construction and mounting and connection of the ignition coil and the distributor head of automobile ignition systems by providing a special construction of distributor head, in which is mounted the ignition coil, having direct connection with the contact for the distributor arm, and also constructed so that a circulation of air 25 will be permitted about the coil, for keeping the same in a substantially cool condition, and in addition eliminating substantially all of the high tension wire connections except those between the distributor head and the spark plug.

A further object of the invention resides 30 in providing a device of the character above mentioned, wherein a body constructed of suitable insulating material is formed with a central bore, in which is mounted the primary, secondary, and core, in proper relation, of an inductance coil, while the same is formed concentrically and adjacent the bore, receiving said induction coil, with a 35 plurality of ventilating passages in order to properly ventilate the induction coil, so that the same may be maintained in a cool

state, rods members being adapted for insertion through the outer peripheral portion of the body adapted to form circuit connections for the high tension wire of the 40 spark plugs and at the same time mount end caps on said body, one of which is adapted to removably fit the distributor, so as to mount the body thereon, in order that the contact on the distributor arm may 45 operate with contacts carried in one of said caps for properly interposing the ignition coil in the ignition circuit of the automobile.

The invention also includes other objects 50 in the details of construction and arrangement of the parts which are more particularly pointed out in the following description and claims; directed to a preferred form of the invention, it being understood 55 that various changes in the details of construction and arrangement of the parts may be made, within the scope of the invention as described and claimed.

In the drawing, forming a part of this 60 application:

Figure 1 is a side elevation of the device, illustrated and mounted on the upper end of the distributor, in the usual manner.

Figure 2 is a vertical sectional view there- 65

Figure 3 is a horizontal section, taken on the line 3—3 of Figure 1.

The improved distributor head and combined ignition coil structure includes a body 1, formed of any suitable insulating material, and preferably of cylindrical form, which is provided in the central portion 70 with an axial bore 2, in which is mounted the ignition coil, including a laminated core 3, a primary 4, and the secondary 5, which as illustrated, forms an integral body adapted to be positioned and cemented or otherwise secured within the bore to the 75 body. Extending longitudinally of the body and adjacent the bore 2 and arranged concentrically with relation thereto, are a plu- 80

rality of air passages 6, adapted to permit of the ready ventilation of the body, in order to maintain the ignition coil, in a sub- 85 substantially cool state, while a plurality of openings are provided adjacent the periphery of the body for receiving the rods 7, which are headed, as indicated at 8, to pro- 90 vide contact points adapted to seat in re- cesses in the attaching cap 9, adapted to 95 be secured over one end of the body, while the other ends of the rod 7 are adapted 100 to 105

110

to receive terminals 10, adapted to be screw threaded or otherwise mounted thereon, for securing the end plate 11 to the opposite end of the body from said cap 9, in order 5 to form a finished structure.

The cap 9 is constructed and adapted for the standard sized distributor indicated generally at 12, which is provided with securing elements, such as indicated at 13, for 10 removably securing the usual cap thereto, which is utilized for the purpose of securing the present invention to the distributor in the manner as illustrated in Figure 1. One terminal of the secondary of the ignition coil is connected to a contact 14, in the cap 9, and positioned centrally thereof for contact with the carbon brush 15 carried in the end of the distributor arm 16, which is rotatably mounted on the distributor 15 shaft 17, while the outer end of the distributor arm 16 is provided with a spring projected contact 18, adapted to engage the inside surface of the cap 9 for contact with the head 8 of said rod 7, in order to complete 20 the secondary circuit to the spark plugs, the leads of which are attached to the terminals 10 on the upper end portion of the body. The terminal of the primary at the lower end of the coil is extended 25 through a transverse passage in the body, and connected to a binding post 19, mounted on the side portion thereof, in order that it may receive the wire connection from the usual controlling switch. The plate 11 is 30 provided with a binding post 20, which receives the common terminal of both the primary and secondary windings of the ignition coil, and is adapted to receive the wire connections from the battery in the usual 35 manner.

One side of the body 1 is formed with a recess 21, in which is mounted a condenser 22, connected in the primary circuit of the inductance coil in a manner well known in 40 the art, for reducing the arcing across the breaker point, a cap being removably positioned over the condenser for closing the recess 21, in a manner clearly illustrated in Figures 1 and 3. A binding post 24 is provided 45 on the side of the body above the cap 23 for one side of the circuit to the condenser, so that it may be properly grounded, in the usual manner, while the other side of the condenser is connected to 50 the wire extending to the binding post 19.

From the foregoing description, it will

thus be seen that a novel construction has been provided for combining a distributor cap and an ignition coil, in a unitary structure, in order to increase the efficiency of 60 operation thereof, and eliminate numerous disadvantages now experienced in the manner of mounting and connecting these elements, which are constructed separate.

In some ignition systems, it is not necessary to combine the condenser in the body structure as illustrated, in view of the fact that a separate condenser construction is connected with the breaker point, in which case the body may be manufactured for attachment to a distributor, without the recess 21 and the remaining structure mounted therein, while the same may also be constructed, as illustrated, for the types of ignition system, requiring the condenser to be 70 associated with the ignition coil, so that by constructing two standard types of distributor heads, according to this invention, having the proper sized cap 9, the same may be immediately applied to all types of distributor heads.

What is claimed is:

A distributor head comprising a cylindrical body having an axial bore and a plurality of passages arranged in circumferential relation around said bore formed therein, an induction coil mounted in the bore, an attaching cap fitted to one end of the body to form a cover and formed for attachment to a distributor section, an end plate mounted on the other end of the body and having openings registering with the circumferentially arranged passages, and a plurality of rods headed at one end and extended through the cap, body and end plate in spaced parallel circumferential relation, having terminals secured thereto to hold the cap, body and end plate, in rigid assembled relation, the heads on the rods forming contacts for cooperation with the distributor, said terminals being formed to receive electrical connection to interpose said rods in the ignition circuit in a predetermined manner, and said body being provided with terminals having electrical connection with predetermined portions of said induction coil, whereby the same may be interposed in the ignition circuit.

In testimony whereof I affix my signature.

WILLIAM MERRILL OLSON.
